United States Patent Office

Des. 211,429

Patented June 11, 1968

211,429

SLIDE-TOP PENCIL SHARPENER

Jack Fairchild Fleming, Summit, N.J., assignor to Sterling Plastics Co., Mountainside, N.J., a corporation of New Jersey

Filed June 21, 1967, Ser. No. 7,541

Term of patent 7 years

(Cl. D74—21)

FIG. 1

FIG. 3

FIG. 1 is a top plan view of a slide-top pencil sharpener embodying my new design;

FIG. 2 is a side elevational view thereof, the opposite side being similar in appearance excepting that there is no opening in the side wall; and

FIG. 3 is a perspective view thereof.

I claim:

The ornamental design for a slide-top pencil sharpener, substantially as shown and described.
